US0D1037753S

(12) United States Design Patent (10) Patent No.: US D1,037,753 S
(45) Date of Patent: * Aug. 6, 2024

(54) COUNTERTOP PIZZA OVEN APPLIANCE

(71) Applicant: Forno Bravo, LLC, Colorado Springs, CO (US)

(72) Inventor: Alex Clark, Colorado Springs, CO (US)

(73) Assignee: Forno Bravo, LLC, Colorado Springs, CO (US)

() Term: 15 Years

(21) Appl. No.: 35/002,269

(22) Filed: Jun. 21, 2022

(80) Hague Agreement Data

Int. Filing Date: Jun. 21, 2022

Int. Reg. No.: DM/222213

Int. Reg. Date: Jun. 21, 2022

Int. Reg. Pub. Date: Jun. 23, 2023
